RIFLED AIR CONTROL NOZZLES

William J. Caldwell, Independence, Mo.

Application June 27, 1951, Serial No. 233,753

4 Claims. (Cl. 98—40)

This invention relates to air nozzle constructions for controlling the contour, direction and diffusion characteristics of pressurized air for heating, cooling, ventilating or other purposes, including the projection of a controlled air stream forming a carrier for a substance, such as abrasive material. In particular, the invention relates to a nozzle construction which is suited to the controlled discharge into a room or building space of the conditioned air pressurized and delivered to the discharge nozzle in accordance with the pressurized air conditioning system disclosed in co-pending application Serial No. 187,258 filed September 28, 1950.

It is an object of the invention to provide an improved nozzle construction which is of compact construction and offers the possibility of accurate and wide range control in regard to the contour, direction and diffusion of the discharged air flow.

Other objects and advantages of the invention will appear clear from consideration of the following description of one practical form of the invention by way of example with reference to the accompanying drawings, in which:

Fig. I is a vertical section, and

Fig. II is an underneath plan view of Fig. I.

In the drawings, 10 is an outer cylindrical casing shown mounted in a ceiling construction 12 and connected at its upper and with a duct system 14, by which pressurized air is delivered into the nozzle cylinder 10 for discharge into a room space from its lower end.

Mounted within this cylinder, in axially extending circumferentially spaced relation, is a series of elongated flexible blades 16, conveniently made from spring steel and arranged to extend in radial disposition from the interior surface of the cylinder.

Each blade 16 is slidably retained at its upper and reduced end 16' in a bracket structure 18 and at its lower end is anchored to a ring structure 20 mounted in an exterior channel section 22 of the cylinder 10 so as to be capable of partaking of limited oscillatory motion by suitable control actuator means.

Each blade is shown with a crank arm 24 at its lower end presenting a vertical portion 24' which is guided for oscillatory motion in an arcuate slot 26 in the bottom of the channel section 22.

The construction and arrangement is such that by appropriate actuation of the ring 20, the blades 16 can be given a twisted set or pitch to a varying extent, in a right or left hand direction, to collectively resemble the rifling of a barrel, by flexure of the blades as their lower ends are displaced on account of the angular motion imparted to the ring 20.

Actuation of the ring 20 can be arranged to be effected in a variety of ways, manually, mechanically or electrically and can be under thermostatic control.

In the drawings, actuation of the ring 20 is arranged to be effected by what is known in the aircraft field as a "linear actuator" including a geared motor and piston assembly, indicated generally at 28, having an extendible

2

and retractable rod element 30 guided for movement in an arcuate slot in the side of the channel section 22 and connected with the ring by a linkage 32.

This linear actuator is characterized by a linear motion of 1 1/4 inches and an energy value of 150 pounds and has been found to give excellent results on nozzles employed to control the discharge of pressure air in heating, cooling or ventilating systems where there is need for concentrating the air flow over large door openings in winter and for the same nozzle installation to distribute air in summer over a more extensive room area. The actuator involves an electrical push button control the mere operation of which results in the pitch of the blades 16 being adjusted as required to thereby control the rotative speed of the air and the conical effect thereby produced.

With the present invention it is possible to control the contour of the discharged air from a cylindrical beam into a diverging cone, or vice versa, in order to produce an effect upon the target against which the air stream is projected, which effect can be changed at will to meet a changing condition of, or at, the target. It is also possible to regulate the characteristic of a stream of air directed against an object under examination, as for reaction to an air stream of pre-conditioned air or, where the air stream is employed to form a carrier for a substance, such as abrasive material, for bombarding an object with such substance.

It is not necessary that the variable blades 16 should extend entirely from the periphery of the nozzle to the center thereof for the purpose of totally controlling the entire air mass.

Having thus described my invention what I claim as new and wish to secure by Letters Patent is as follows:

1. In a nozzle construction for the controlled discharge of pressure air, a cylinder casing having inlet and outlet ends, a series of flexible blade elements disposed in said casing in axially extending circumferentially spaced relation to define air flow passages, and means mounting said blade elements adjacent the interior surface of said casing, said mounting means including means guidingly supporting the blade elements at one end adjacent the said inlet end, ring means at the said outlet end mounting the corresponding ends of the blade elements for bodily rotary motion relatively to said cylinder about its central longitudinal axis and means for actuating said ring and for holding it against rotation between actuations.

2. The invention as defined in claim 1, said blade elements being of spring material.

3. The invention as defined in claim 1, said blade elements being slidably mounted by said first means at said inlet end, said blade elements being rigidly connected against longitudinal movement at the said outlet end with said ring means.

4. The invention as defined in claim 1, said mounting means for said flexible blade elements supporting said elements for flexure in opposite directions by actuation of said rotary mounting means, whereby to enable the pitch of said air flow passages to be varied, said means guidingly supporting the blade elements at one end comprising a sliding connection at one end of each of said elements and said ring means at said outlet end comprising a pin and sleeve connection at the other end of said elements.
